[57] CLAIM

The ornamental design for a wall mounted vanity, substantially as shown.

DESCRIPTION

FIG. 1 is a perspective view of a wall mounted vanity showing our new design in its opened condition; FIG. 2 is a front elevational view thereof, in its closed condition.

FIG. 3 is a right side elevational view thereof;

FIG. 4 is a top plan view thereof;

FIG. 5 is a left side elevational view thereof;

FIG. 6 is a rear elevational view thereof; and

FIG. 7 is a bottom plan view thereof.

FIG. 1
